ROD CEMENT EXTRUDER

Albert E. Newton, Beverly, Mass., assignor to United Shoe Machinery Corporation, Boston, Mass., a corporation of New Jersey

Filed July 29, 1963, Ser. No. 76,024

Term of patent 3½ years

(Cl. D54—13)

Fig. 1

Fig. 2

Fig. 3

Fig. 4

FIG. 1 is a perspective view of a rod cement extruder showing my new design;

FIG. 2 is a side view of the extruder;

FIG. 3 shows the extruder as viewed from the top; and

FIG. 4 shows the extruder as viewed from the front.

The undisclosed side is substantially the same in appearance as the side shown.

I claim:

The ornamental design for a rod cement extruder, as shown and described.
